R. W. UHLIG.

TYPEWRITING MACHINE

Filed April 30, 1923

Inventor
Richard W. Uhlig
By his Attorney *John O. Seifert*

UNITED STATES PATENT OFFICE.

RICHARD W. UHLIG, OF NEWARK, NEW JERSEY, ASSIGNOR TO ALLEN TYPEWRITER MANUFACTURING COMPANY, OF ALLENTOWN, PENNSYLVANIA, A CORPORATION OF PENNSYLVANIA.

TYPEWRITING MACHINE.

Application filed April 30, 1923. Serial No. 635,588.

To all whom it may concern:

Be it known that I, RICHARD W. UHLIG, a citizen of the United States, and resident of Newark, in the county of Essex and State of New Jersey, have invented certain new and useful Improvements in Typewriting Machines, of which the following is a specification.

This invention relates to typewriting machines of the front strike type in which bars fulcrumed or pivotally supported at one end and carrying type at the opposite ends are actuated by finger key levers to be moved from a normal position of rest to contact with the front of a platen and returned to position of rest upon the removal of pressure from the finger keys. In this type of machine to compensate for unevenness in touch of the operator upon the actuating of the finger key levers with a resultant unequal inking of printed characters, and to also prevent the typebar from too forcibly impinging the type against the writing sheet on the platen with the possibility of cutting the sheet by the type, and thereby also the wearing of the type, an abutment or stop with which the typebars engage or contact at the time of or just previous to the type striking against the platen to thereby limit and retard the movement of a typebar toward the platen. In the provision of an abutment for this purpose constructed integral with the typebar carrying segment in the form of a rib projecting from the segment owing to inequalities and irregularities in the typebars, due to springing and distorting by hardening and otherwise, considerable time is required to adjust the typebars by bending and springing the same in order to properly aline the typebar to cause the type of successively actuated bars to impress the type successively in true alinement upon the writing sheet upon the platen.

It is the object of the present invention to provide an improved construction and arrangement of typebars and abutment for the typebars to contact with to limit the movement thereof toward the platen, said abutment while being rigid for the engagement of the typebars at the same time being pliable and adjustable to permit of the movement of the typebars to a greater or less extent

toward the platen and thereby obviate the necessity of bending and springing of the typebars to cause them when actuated to properly impinge against the platen, and thereby also greatly facilitate the alinement of the typebars and type.

Other objects and advantages will herein-after appear.

In the drawing accompanying and forming a part of this specification Figure 1 is a side elevation of a typebar action of a typewriting machine and a segment therefor showing an embodiment of my invention, only so much of a typewriting machine being shown as is essential to an understanding of the invention; and

Figure 2 is a perspective view of a portion of the segment showing the arrangement of my improved typebar abutment or stop mounted thereon.

Similar characters of reference designate like parts throughout the different views of the drawing.

In carrying out the embodiment of the invention shown in the drawing a segment 3 is suitably mounted in the framework of the machine and arranged with a seat 4 for the engagement of a support 5 in the form of a wire or rod upon which typebars 6 are fulcrumed or pivotally supported at one end and carry type 7 at the opposite end, the segment being slotted as at 8, for the engagement of the typebars and to guide the bars as they are actuated to strike rearwardly against the front of a platen 9. The slotted portion of the segment has an overhang 10 to direct foreign matter, such as erasings made on the writing sheet upon the platen, away from the bearing support of the typebars. The typebars are actuated by levers 12 pivotally supported in the framework, as at 13, having finger keys 14 at the forward ends and operatively connected to the typebars 6 by links 15. These levers are normally in the full line position shown in Figure 1 with the typebars normally at rest upon a support 16. As the key end of a lever is depressed to the dotted line position the connected typebar through its link connection is moved upward and swung toward the front of the platen, and as the pressure is removed from the key end of the lever the lever is returned by a spring 17.

The segment 3 is arranged so that the typebar supporting fulcrum rod 5 is substantially in a plane that the front of the platen is in the same plane. To limit the movement of the typebars toward the platen each of the typebars is arranged with a heel or projection 18 extending from the rear or with the edge of the typebar to which the bar carrying head 7 is connected, said projection having an inclined or beveled face 19. An abutment member 20 in the form of a comb is mounted in fixed position upon the top of the segment, as by screws 21, with the teeth 22 of the comb in line with and projecting over the segment slots 8 and in line with the path of movement of the typebars. As a typebar is moved to printing position against the platen the inclined face 19 of the typebar heel 18 will contact or engage with a tooth 22 of the comb arresting the movement of the typebar, and this contact of the typebar with this comb tooth may be arranged to be simultaneous with the contact of the type against the platen, but is preferably arranged so that the typebar will contact with said comb tooth just previous to the contacting of the type with the platen whereby the impact of the typebar against the comb tooth will cause the typebar to be sprung and impinge or contact the type against the platen. The material of the abutment or comb 20 is rigid though pliable, and should it be found that sufficient movement is not being imparted to a typebar by the operation of its key lever to cause the type to strike against the platen, or to strike too forcibly against the platen, the tooth of the abutment with which said typebar co-operates is adjusted upwardly or downwardly in a direction in line with the movement of the typebar thereby causing the inclined face 19 of the typebar projection to come into contact earlier or later in the movement of the typebar.

From Figure 1 it will be noted that the type of the typebar shown in full lines is in contact with the platen with the incline face 19 of the typebar in contact with the end of a comb tooth extending horizontally outward from the segment. Should the tooth be adjusted to or should it initially have been in the position indicated in dotted lines, the inclined face 19 would be caused to contact with the end of the comb tooth too early and the typebar would be permitted to move only to the position indicated in dotted lines. Should the comb tooth be adjusted downwardly from the horizontal, the incline face 19 would contact therewith later in the travel of the typebar and permit the typebar to move to a greater extent toward the platen. The typebars are guided in their movement to the platen by a guide 25 suitably mounted upon the segment.

By the arrangement as above described I

not only provide an adjustable abutment or stop for the typebars, but by the arranging of the teeth of the comb in line with the segment slots any erasings from the writing sheet on the platen will be directed away from such slots.

Having thus described my invention, I claim:

1. In a typewriting machine, the combination with a platen and fulcrumed typebars adapted to be swung to printing position relative to the platen, of a comb mounted in fixed position between the fulcrum support of the typebars and platen with the teeth of the comb arranged in line with the movement of the typebars adapted to be engaged by the typebars and limit the movement thereof toward the platen, and said teeth adapted to be adjusted in a direction with the movement of the typebars to project to a greater or less extent into the path of movement of the typebars for the purpose specified.

2. In a typewriting machine, the combination of a platen; a fulcrumed typebar normally positioned out of contact with the platen and adapted to be swung to printing position in contact with the platen, said typebar having a projection extending from one edge arranged with an inclined face; and a rigid abutment interposed between the typebar and platen having an adjustable portion projecting into the path of movement of the typebar to be engaged by the inclined face of the typebar projection to limit the movement of the typebar toward the platen.

3. In a typewriting machine, the combination of a platen; a segment; typebars pivotally carried by the segment each having a projection with an inclined face; and a rigid member mounted upon the segment arranged with individual abutments projecting into the path of movement of each of the typebars to be engaged by the inclined face of the typebar projections in the movement of the typebars toward the platen.

4. In a typewriting machine, the combination of a platen; a slotted segment; typebars pivotally supported in the slots of the segment; finger key levers operable to swing the typebars toward the platen; and a rigid comb member mounted upon the segment arranged with projections extending in line with the slots of the segment and in the path of movement of and to be engaged by the typebars to limit the movement thereof toward the platen.

5. In a typewriting machine, the combination of a platen; a slotted segment, typebars pivotally supported in the slots of the segment; finger key levers operable to swing the typebars toward the platen; and a rigid comb mounted upon the segment with the teeth thereof to project over the segment

slots in the path of movement of and to be engaged by the typebars to limit the movement thereof toward the platen.

6. In a typewriting machine, the combination of a platen; a slotted segment; typebars pivotally supported in the slots of the segment, each bar having a projection extending from one edge intermediate the ends and arranged with an inclined face; finger key levers operable to swing the typebars to printing position relative to the platen; a comb fixed to the segment with the teeth

thereof to extend over the segment slots and in line with the path of movement of the typebars to be engaged by the inclined faces of the typebar projections, and said comb teeth adapted to be adjusted in a direction in line with the movement of the typebars to limit the movement thereof toward the platen. 15
